UNITED STATES PATENT OFFICE.

FERDINAND S. WOLDRIDGE, OF BROOKLYN, NEW YORK.

DISPLAY-CABINET.

No. 927,626.

Specification of Letters Patent.

Patented July 13, 1909.

Application filed April 22, 1909. Serial No. 491,578.

To all whom it may concern:

Be it known that I, FERDINAND S. WOLDRIDGE, a citizen of the United States, residing at Brooklyn, in the county of Kings and State of New York, have invented certain new and useful Improvements in Display-Cabinets; and I do declare the following to be a full, clear, and exact description of the invention, such as will enable others skilled in the art to which it appertains to make and use the same.

This invention relates to display cabinets of that class which comprises a plurality of display drawers which are mounted bodily, one upon the other, in order that all of the drawers may be pulled out by one operation.

A further object is to provide limiting means for the drawers of such a nature that when pulled completely out they will be arranged in stepped relation or with each drawer in advance of the next upper drawer in order that the goods in the several drawers may be equally well displayed.

With these and other objects in view, the invention consists of certain novel features of construction, combination and arrangement of parts as will be more fully described and particularly pointed out in the appended claim.

30 In the accompanying drawings, Figure 1 is a front elevation of the display cabinet with the glass front raised; Fig. 2 is a central vertical longitudinal section with the glass front down and with the drawers closed; Fig. 3 is a similar view with the drawers in their extreme outward position and the glass front raised; Fig. 4 is a vertical transverse section taken on line 4—4 of Fig. 2; and Fig. 5 is a detail perspective of one of the drawers.

40 In the embodiment illustrated the device comprises an approximately square casing, 1, provided at its top with a glass, 2, and with a front hinged section, 3, provided with a glass, 4, adapted to be folded upon the top of the casing or in position shown in Fig. 3. A plurality of display drawers, 5, are mounted bodily, one upon the other, within the casing so that when the lower drawer is pulled out the remaining drawers are carried with it.

50 As heretofore explained the principal object of the invention is to provide limiting means

whereby when the drawers are pulled out to their extreme forward positions they are arranged in stepped relation or with each drawer extending in advance of the next upper drawer so that the contents of all of the drawers may be equally well displayed. To accomplish this the inner face of each side member, 6, of the casing is provided with a series of longitudinal grooves, 7, 8 and 9 respectively, which extend from the rear edge thereof and beginning with the top of said member, each groove being made somewhat longer than the next upper groove. The side pieces, 10, of the drawers are provided near their rear ends with lateral studs or pins, 11, which fit in the grooves of said side members. It will thus be seen that in pulling out the drawers the lower drawer will extend the farthest to the front, the next upper drawer somewhat in the rear of the lower drawer and so on for all the drawers.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention.

Having thus described my invention, what I claim is:—

A display cabinet of the class described comprising a casing, a series of sliding drawers mounted bodily, one upon the other, in the casing; means for limiting the forward movement of the drawers, a front section hinged to the top of the casing and adapted to swing upwardly thereon, the hinged end of said section being of greater width than its free end and adapted to rest upon the top of the casing and form a support when said section is raised.

In testimony whereof I have hereunto set my hand in presence of two subscribing witnesses.

FERDINAND S. WOLDRIDGE.
